US0D1102813S

(12) **United States Design Patent** (10) **Patent No.:** **US D1,102,813 S**
(45) **Date of Patent:** **** Nov. 25, 2025**

(54) **ADDITIVE VESSEL**

(71) Applicant: **Cirkul, Inc.**, Tampa, FL (US)

(72) Inventors: **Mark Lyons**, Ashburn, VA (US);
Robert Lawson-Shanks, Reston, VA (US); **Jonathon Perrelli**, Leesburg, VA (US); **Justin Toelle**, Washington, DC (US); **Benjamin Gillette**, Reston, VA (US); **Simon Lewis Bilton**, Leamington Spa (GB); **Adam Harvey-Cook**, London (GB); **Matthew James Edwards**, Leamington Spa (GB)

(73) Assignee: **Cirkul, Inc.**, Tampa, FL (US)

(**) Term: **15 Years**

(21) Appl. No.: **29/974,044**

(22) Filed: **Nov. 20, 2024**

Related U.S. Application Data

CLAIM

The ornamental design for additive vessel, as shown and described.

DESCRIPTION

FIG. 1 is a front perspective view of an additive vessel showing the new design;

FIG. 2 is a bottom perspective view thereof;

FIG. 3 is a front view thereof;

FIG. 4 is a rear view thereof;

FIG. 5 is a right view thereof;

FIG. 6 is a left view thereof;

FIG. 7 is a top view thereof; and,

FIG. 8 is a bottom view thereof.

The broken-line showing of various elements of the additive vessel in FIGS. 1-8 is for environmental purposes only and forms no part of the claimed design.

1 Claim, 8 Drawing Sheets

Related U.S. Application Data

a division of application No. 29/632,269, filed on Jan. 5, 2018, now Pat. No. Des. 887,769.
